UNITED STATES PATENT OFFICE.

JOHN M. FOTCH, OF CHICAGO, ILLINOIS.

AUTOMATIC AIR AND GAS CHECK VALVE.

Application filed November 22, 1924. Serial No. 751,592.

This invention relates to a novel automatic air and gas check valve and vent particularly adapted for refrigerators and the like.

5 It is a well-known fact that meats, fish, vegetables, fruits, and many other foods, generate and give off certain gases, therefore, when such foods are stored in refrigerators or ice boxes containing other gas absorbing 10 foods, the latter will be contaminated. In other words, the gases from certain foods naturally contaminate other foods contained in the refrigerator or ice box and destroy the original flavor if not the substance of 15 the same when stored together. However, owing to the fact that these gases are lighter than air, they always rise to the top of the refrigerator or ice box, therefore, a means of escape or vent should be provided at or 20 near the top of the refrigerator or ice box to permit them to escape and thus avoid the absorption of the same by the foods contained therein.

The object of this invention is to provide 25 a means for permitting gases and other impurities generated by meats, fish, vegetables, fruits and other food products to escape through a vent or outlet and thus prevent the absorption of these gases by the food 30 or contents of the refrigerator or ice box.

A further object is to provide the vent 35 with a balanced valve, the normal position of which is open, to permit gases to escape from the refrigerator or ice box, and also to automatically close the valve when suction is created within the refrigerator, or 40 ice box, by the opening of either of the doors thereof, so as to prevent any gases or impure air which may lurk in the room or surroundings in which the refrigerator or ice box is located from being sucked into the same.

With the above and other objects in view, 45 the invention consists of certain novel combinations and arrangements of parts to be hereinafter more fully described and claimed.

In the accompanying drawings Fig. 1 is 50 a front elevation partly broken away showing my improved vent or automatic air and gas check valve applied to a refrigerator or ice box.

Fig. 2 is an enlarged sectional view showing the wall of the refrigerator with the device applied and in section.

Fig. 3 is a view similar to Fig. 2 but 55 showing the vent valve open as distinguished from the closed position shown in Fig. 2.

Figs. 4 and 5 are transverse horizontal 60 sectional views taken on the section lines 4—4 and 5—5 of Fig. 2, and

Fig. 6 is a fragmentary detail perspective view of the lower end of the vent.

In the drawings, in which like reference 65 characters designate corresponding parts throughout the several views, 2 represents a flanged casing or tube formed of tin or any other material which fits snugly within the walls of the refrigerator 1, preferably centrally at the top, or at any other suitable position, and is permanently held in place 70 by means of nails, screws or the like 3. The said tube is intended to receive a casing or tube 4 of smaller diameter which projects slightly above the refrigerator wall or top, 75 and is provided at its upper end with a circular flange 5 in the form of an internal annular flange preferably of angular cross section, which is rigidly affixed to the inner side 80 of the tube and forms a seat for a disc or valve 6, having openings or apertures 6' 85 therein. The disc or valve 6 is intended to close an aperture 7 in the flange when the disc is drawn downwardly by the suction or vacuum created in the refrigerator by the opening of the refrigerator doors or door. 90

The disc 6 is secured to a vertical rod 8, the lower end of which is affixed to a pivoted weight 9 as shown at 10, said weight 9 being pivotally secured to the tube 4 as 95 shown at 11 and rests against a stop 12 when the valve is in its open or normal position.

It will be noted that when the valve is 100 in the latter position, the gases are permitted to pass through the tube 4 and out through the aperture 7 thus venting the refrigerator or permitting the gases to escape and keeping the refrigerator properly ventilated with only fresh, pure and sanitary air present 105 therein and preventing the food from becoming contaminated by the undesirable gases produced by the food in the refrigerator. It will be appreciated that if the vent tube 4 was not provided with a valve for automatically closing the aperture 7, undesirable gases, or smoke, soot and dust would be sucked through the tube 4 whenever it became necessary to open the refrigerator door 110.

to remove or place food in the refrigerator or for other purposes, such as placing ice therein.

In order to permit the tube 4 to be readily removed when it is necessary to clean the same or the refrigerator, the said tube 4 is provided with an annular recess 13, which is intended to receive an annular rubber or like washer 14, the purpose of which is to hold the tube 4 in place by means of friction. As shown, two of such washers are employed near the top and bottom portions of the tubes or upper and lower ends thereof. These washers serve to form an airtight joint between the outer tube 2 and the inner tube 4. The lower end of the latter tube is provided with a lug 15, which has an aperture 16 intended to receive a hook which permits the removal of the inner tube 4 from the outer tube 2 whenever it becomes necessary or desirable to remove it. It is obvious from the construction shown that the inner tube 4 can be readily placed within the outer tube 2 by simply forcing the same in an upward direction until the same is flushed with the inner tube wall of the refrigerator. It is also desirable to provide the upper and lower ends of the tube 4 with screened covers or discs 17 and 18 for the purpose of preventing foreign matter, flies, etc. from entering the same, thereby keeping the tube clean and insuring proper operation of the device as well as insuring cleanliness and sanitary condition within the refrigerator. By this means, the food is also protected.

While I have described the form of my invention which I now consider to constitute the preferred embodiments, it is to be understood that changes in the details of construction and arrangements of parts may be resorted to without departing from the spirit and scope thereof so long as the same is defined by the device as claimed.

Having thus described my invention, what I claim is:

1. A vent of the class described comprising a tube, a seat near the top of the tube, a disc co-operating with said seat, a weight pivoted in the tube, a connecting rod extending from the disc to one arm of the pivoted weight, a means for limiting the movement of the weight.

2. In an automatic air and gas check valve of the class described, a tube, an apertured seat mounted near the upper end of the tube, a disc co-operating with said apertured seat, a weight pivoted intermediately near the lower end of the tube and within the same, one arm of the weight being connected to the disc, and a stop to limit the downward movement of the weight.

3. An automatic air and gas check valve comprising a tube, screens at the top and bottom ends of the tube, an apertured flanged seat near the top end of the tube,

a disc co-operating with said seat, a weight pivoted intermediately in the tube near the bottom thereof, a rod connecting one arm of the weight centrally to the disc, and a pin mounted beneath the weighted end of the weight arm to limit the downward movement thereof.

4. In an automatic air and gas check valve for venting refrigerators and the like, an outer tube having a flange for securing the same snugly within the wall of the refrigerator, an inner tube, air-tight connections between the inner and outer tubes, a seat near the top of the inner tube having an aperture therein, a disc co-operating with said seat, a rod secured to the disc and depending therefrom in the tube, a weighted member pivoted in the tube near the lower end thereof and having an unweighted end connected to the lower end of the rod, the weighted end being adapted to move downwardly, and a stop to limit the downward movement of the weighted end.

5. In a vent or automatic air and gas check for refrigerators or the like, the combination with the wall thereof having an opening, of a tube snugly fitting in said opening and having a flange secured thereto at the bottom, an inner tube secured within the outer tube, rubber washers mounted in grooves in the inner tube and frictionally engaging the outer tube to secure the inner tube within the outer tube and form air-tight connections therebetween, said inner tube projecting above the outer tube, a flanged apertured seat in the projecting end of the inner tube, a disc co-operating with said seat, a weight pivoted in the inner tube near the lower end thereof, one arm of the weight being connected to the lower end of the rod whereby when the weighted end moves outwardly, the disc will be raised, said disc having openings therein to permit the escape of the impure air within the refrigerator through said tubes, a stop limiting the downward movement of the weight and opening of the disc, and an apertured lug projecting from the inner tube to permit removal thereof.

6. In a vent for refrigerators, an outer tube adapted to be mounted in the wall of a refrigerator, an inner tube mounted therein, washers frictionally retaining the inner tube within the outer tube and forming an air-tight connection in space therebetween, means at the lower end of the inner tube for removing the same from the outer tube, and a weight operated valve mounted in the inner tube, said valve being normally open and adapted to be closed by the opening of a refrigerator door due to the suction created therein.

7. A vent for the purpose described, comprising a casing, one end of which is open to the atmosphere outside of the refrigerator,

- ator, and the other end to the interior thereof, an apertured seat fixed within said casing near one end thereof, and a normally opened balanced disc co-operating 5 with said apertured seat, for closing the end of the casing open to the atmosphere outside of the refrigerator, whenever suction is created within the refrigerator by the opening of the doors thereof.
- 10 8. In a vent or automatically operated air and gas check for refrigerators or the like, the combination with the wall thereof, having an opening, of a casing snugly fitting in said opening, and having a flanged end, 15 an inner casing removably secured within
- the outer casing, a compressible washer affixed to the exterior of the inner casing for frictional engagement with the outer casing to secure the inner casing within the outer casing and form air tight connections 20 there-between, an apertured seat fixed within the inner casing near one end thereof and a normally open balanced disc co-operating with said apertured seat, for closing the end of the casing open to the atmosphere 25 outside of the refrigerator, whenever suction is created within the refrigerator by the opening of the doors thereof.

In testimony whereof I affix my signature.

JOHN M. FOTCH.
